(57) **CLAIM**

The ornamental design for an over-the-cabinet organizer bar, as shown and described.

DESCRIPTION

FIG. 1 is a perspective view of an over-the-cabinet organizer bar showing my new design;

FIG. 2 is a rear elevational view thereof;

FIG. 3 is a front elevational view thereof;

FIG. 4 is a side elevational view thereof;

FIG. 5 is a bottom plan view thereof; and,

FIG. 6 is a top plan view thereof.

The broken-line disclosure in the views is understood to represent unclaimed portions of the article in which the claimed design is embodied.
